UNITED STATES PATENT OFFICE

THOMAS L. PARKER, OF CHICAGO, ILLINOIS, ASSIGNOR TO THE STANDARD ELECTRIC MANUFACTURING CO., OF CHICAGO, ILLINOIS, A CORPORATION OF ILLINOIS

SWITCH KNOB

Original application filed December 27, 1926, Serial No. 157,184. Divided and this application filed March 1, 1928. Serial No. 258,197.

This invention relates to improvements in switch knobs and more particularly to knobs of the character which are used in connection with snap switches.

- 5 An object of applicant's invention is the production of a switch knob which may be quickly assembled and attached to the stem of a rotary snap switch, thereby effecting a great saving in time.
- 10 Another object of applicant's invention is the production of a knob for a rotary snap switch which will resiliently secure the cover for the movable parts in place.

Another object of applicant's invention is 15 the production of a construction which will permit the use for switch knobs of materials such as porcelain and others in which metals are not readily molded or cast.

A further object of applicant's invention 20 is the provision of a switch knob of the above type including in its construction, preferably a non-conductive body having a bore and a sleeve positioned within the bore with a coil spring surrounding the same together with 25 improved means seated within the outer open end of the bore cooperating with the sleeve whereby to restrain displacement of the sleeve.

A further object of applicant's invention 30 is the production of a switch knob of low cost, durable, of a small number of parts, and highly satisfactory for its intended purpose.

Many other objects and advantages of the 35 construction herein shown and described will be obvious to those skilled in the art from the disclosure herein given.

To this end my invention consists in the 40 novel construction, arrangement and combination of parts herein shown and described, and more particularly pointed out in the claims.

In the drawing, wherein like reference 45 characters indicate like or corresponding parts:

Fig. 1 is a top plan view of a device applied to a rotary type of electrical switch;

Fig. 2 is a sectional elevation thereof;

Fig. 3 is an end elevation looking into the 50 bore;

Fig. 4 is a perspective view of the sleeve and spring retaining member;

Fig. 5 is a sectional elevation of a modified form of the invention; and

Fig. 6 is a sectional elevation of another 55 modified form of the invention.

Referring now to the drawing, in Fig. 1 is shown the improved switch knob 1 applied to a snap switch generally indicated by the reference character 2. At 2' is shown the cover for the contact assembly. The knob consists of a base 3 which may be of any suitable contour such as round, oblong, etc., and is shown with wings 4. Within the base 3 is a bore 5 of a contour such that the head 6 on the sleeve 7 is constrained to rotate with the base 3 but may move in and out of the bore 5. The term "sleeve" is here used to include a solid or partially solid construction. About the sleeve 7 is a spring 8. A combined sleeve supporting spring retaining member 9 is positioned within the end of bore 5 and preferably in an enlarged portion 10 thereof. The member 9 is formed with an aperture 11 at the center thereof and preferably with a plurality of 70 fingers 12 at its outer edge. The fingers 12 are preferably resilient in character and engage the inner wall of the enlargement 10 which is molded with an undercut so that it provides a substantial anchor for the ends 80 of the fingers 12. As shown in Fig. 2, the enlargement 10 of bore 5 is formed with a larger diameter at the inner end thereof, thus forming a tapering wall as shown at 13, and providing a substantial anchor for the fingers 12. 85

The sleeve 7 may be formed with a bore 14 which is threaded to screw onto a stem 15. Any other means for securing the sleeve 7 to the stem 15 obviously may be provided. In assembling, the sleeve 7 is positioned such 90 that the head 6 thereof passes into bore 5 first. The spring 8 is then slipped over the sleeve 7 and the combined spring retaining sleeve supporting member 9 is then pushed into the enlarged portion 10 with the fingers 12 pointing outward. When the member 9 engages the shoulder 16, the fingers 12 due to their resiliency firmly engage the walls of the bore 10 and are locked in place due to the shape and contour of the wall.

The form shown in Fig. 5 is in all respects similar to the form shown in Fig. 2 except that a bead 17 is provided in the enlargement 10, as an anchor for the fingers 12, and the enlargement 10 otherwise may be of uniform diameter. In the form shown in Fig. 6, the enlargement may be more or less of uniform diameter except that a small shoulder or undercut 18 is provided which the fingers 12 engage. It is thus seen that the member 9 is securely held in the enlargement 10. It is thus seen that a highly efficient device is provided, satisfactory for its intended purpose. This application comprises a division of my copending application Serial No. 157,184, filed December 27, 1926.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. A device of the kind described, a body portion having a bore, said bore having an enlarged end thus forming a shoulder, a sleeve with an enlarged portion arranged within said bore and constrained to rotate with said body portion, a member within said enlarged end of said bore and embracing said sleeve, said member abutting said shoulder, fingers on said member, and means in said enlarged portion of said bore forming an abutment for said fingers.

2. A device of the kind described, a body portion having a bore, a sleeve with an enlarged portion slidably arranged within said bore and constrained to rotate with said body portion, a member within said bore and fitting over said sleeve, said member provided with a plurality of fingers, means in said bore forming an abutment for said fingers, and resilient means engaging said member and said enlarged portion of said sleeve.

3. A device of the kind described, a body portion having a bore, said bore having an enlarged end forming a shoulder, a sleeve with an enlarged portion slidably arranged within said bore and constrained to rotate with said body portion, a member within said enlarged portion and engaging said shoulder, said member embracing said sleeve, said member having fingers thereon, means in said enlarged portion of said bore providing an abutment for the ends of said fingers, and resilient means between said member and said enlarged portion of said sleeve.

4. In a device of the kind described, a body having a bore closed at one end, the open end of said bore being enlarged, the walls of the enlarged portion of said bore being constricted adjacent its open end, and a member

mounted on the sleeve in the enlarged portion of the bore, said member having a plurality of detent fingers engaging said restricted portion of the bore.

5. In a device of the kind described, a body having a bore closed at one end, the open end of said bore being enlarged, thus forming a shoulder, walls of the enlarged portion of said bore being constricted adjacent the open end of the bore, a member mounted on the sleeve in the enlarged portion of the bore, said member abutting said shoulder and having a plurality of forwardly extending detent fingers engaging the restricted portion of said bore.

6. In a device of the kind described, a body having a bore closed at one end, the open end of said bore being enlarged, thus forming a shoulder, a constricted portion in said enlarged portion of the bore forming a shoulder oppositely disposed to the first mentioned shoulder, a sleeve arranged within said bore and projecting into said enlarged end, a member within said enlarged end and abutting said shoulder, said member embracing said sleeve, means for retaining said member against said first mentioned shoulder, said means comprising forwardly extending fingers on said member engaging said second mentioned shoulder.

In testimony whereof, I have hereunto signed my name.

THOMAS L. PARKER.
